[57] CLAIM

The ornamental design for a washcloth, as shown and described.

DESCRIPTION

FIG. 1 is a top view of a washcloth showing my new design; FIG. 2 is a front side elevational view with the rear side being a mirror image thereof;

FIG. 3 is a right side elevational view with the left side being a mirror image thereof;

FIG. 4 is a bottom view thereof; and,

FIG. 5 is an environmental perspective view of the washcloth in a use thereof.

The broken line showing of the human figure and the shower head in FIG. 5 is for illustrative purposes only and forms no part of the claimed design.
